(57) **CLAIM**

The ornamental design for a point-of-sale printer, as shown and described.

DESCRIPTION

FIG. 1 is a right front perspective view of a point-of-sale printer;

FIG. 2 is an top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a right rear perspective view thereof.

The claimed point-of-sale printer is used to process transactions.

The broken lines depict environmental subject matter and form no part of the claimed design.

1 Claim, 7 Drawing Sheets
